BASKETBALL BACKSTOP

Norval J. Johnson, Elmhurst, and Edward W. Schultz,
Tinley Park, Ill., assignors to Porter Athletic Equipment
Company, Schiller Park, Ill., a corporation of
Illinois

Filed Mar. 16, 1961, Ser. No. 64,320

Term of patent 14 years

(Cl. D34—5)

FIG. 1 is a view in front elevation of a basketball backstop, showing our new design.

FIG. 2 is a view in side elevation of the same.

The broken line showings of supports are for illustrative purposes only.

The dominant feature of our design resides in the planar triangular head bracket having an elongated centrally depending planar leg portion widely spacing and positioning therefrom a backstop board of substantially equal width with said widely spaced planar triangular head portion.

We claim:

The ornamental design for a basketball backstop, as shown and described.
